Shepherd Campbell

ATTORNEY.

UNITED STATES PATENT OFFICE

ERNEST H. WRIGHT, OF KANSAS CITY, MISSOURI

METHOD OF MANUFACTURING MEAT CURE

Application filed November 22, 1927. Serial No. 235,022.

This invention relates to a method of manufacturing meat curing materials, and to the product resulting therefrom. For many years, it has been recognized that meats cured by the smoke of certain of the hard woods, such as hickory for example, have a very delightful flavor, and meats cured by smoking in the manner indicated, have become a delicacy, and command a very high price. However, the method of curing meats by hanging them up in a smoke house and exposing them to wood smoke over a considerable period of time, is so slow and, consequently, so expensive that ways have been eagerly sought for accomplishing substantially the same result in a more economical way. Having, upon one occasion, observed a drip from a stove pipe, burning hard wood, I conceived the idea of condensing the gases driven off from hard wood and of utilizing the resultant liquid in the curing of meats. These liquids were placed upon the market and found widespread favor in the trade. Other products embodying this artificially prepared "liquid smoke" then appeared upon the market, one of these comprising common salt constituting the carrier for the said liquid smoke, which will hereinafter be referred to as the condensate.

The object of the present invention is to produce an improved product of the character last referred to, wherein the salt acts as the carrier for the condensate, but wherein the salt is caused to carry a great deal more of the condensate in proportion to the bulk of the salt than is the case with known products of this character. By my improved method I am able to cause the salt to take up a very great deal more of the condensate than it has been possible to cause the salt to take up by methods heretofore employed.

Furthermore, by my improved method I free the condensate of certain objectionable and even injurious substances, particularly wood alcohol, and I so treat the condensate as to dehydrate it before bringing it into union with the salt.

The figure shown in the accompanying drawing diagrammatically illustrates my method.

In carrying out the method of the present invention I proceed as follows:

A suitable hard wood, such as hickory for example, is charged into the revolving retort 5 of a still, such as those commonly employed for the destructive distillation of wood. At the beginning of the run, which is usually in the morning, the temperature is maintained at from 100 to 160° F. At these temperatures a very substantial part of the gases 60 which contain wood alcohol, are driven off. These gases are permitted to escape from the system through a pipe 6, leading to a barrel 7, this pipe being known as the retort drip. During the time that these lighter vapors are 65 being driven off, a valve 8, which controls the communication of the interior of the retort with the condenser 9 of the still, is kept closed, and thereafter said valve is opened and the vapors driven off from the wood are permitted to pass into the coils of the condenser, which are kept cooled in any suitable and conventional way, such as by running water over them. The temperature of the retort is raised as the run progresses, being gradually increased through the day to a maximum of about 900° F. This slow increase in temperature results in driving off successively heavier fractions and all the fractions which pass through the condenser, and which are condensed therein are delivered to a suitable container 10. A vent 11, at the top of the condenser permits the escape of certain uncondensable and undesirable vapors, such as carbon dioxide and carbon monoxide. It has been found that the material discharge through the retort drip 6, at the beginning of the run, consists of wood alcohol, light oils, and some pyroligneous acid, and that of this material substantially 18% is wood alcohol.

Thus it will be seen that a very substantial proportion of this objectionable agent is gotten rid of by the simple expedient of discharging those fractions first released at relatively low temperatures completely from the system, before permitting any of the vapors to pass into the condenser and before permitting any of the condensate to pass to the container 10.

While, for purposes of explanation, I have

illustrated all of the apparatus as being so connected as to carry out the process in a continuous manner, it is to be understood that this is not essential, but that the material delivered to the container 10 may be led directly therefrom for further treatment, or may remain there until needed, and may be taken therefrom, either through a pipe leading to some other unit, or in manually handled containers, such as buckets or the like. However, this transfer may be effected, the condensate is next delivered from the container 10 to a conventional type of vacuum still 12, for the purpose of dehydrating the same. The result of dehydrating is to very considerably increase the degree of concentration of the condensate. While the degree of concentration may be varied within wide ranges, I have, by dehydration, converted a quantity of the material having a specific gravity of 1.013 to a very much heavier concentrate of anhydrous residue comprising 47.75% of the original quantity. The final heavy concentrate is brought into intimate admixture with the crystals of common salt, of a degree of fineness approximating that of table salt, by spraying this material while in a heated condition upon the salt crystals at a time when they are in a state of suspension and agitation. This is accomplished by conducting the heated condensate from the vacuum still 12, through a suitable tube 13, to the container 14 of a conventional type of spray gun, such as those commonly employed in the arts for the application of paint, varnishes and the like. Compressed air delivered from a compressed air container 15, through a tube 16, is delivered to the spray gun after being passed through a heater 17, which preheats the air. It is, of course, apparent that a condensate of the character described would become more or less thick and viscous when cold. By preheating the air and by using the condensate in a heated condition, and by delivering the whole forcibly through a spray gun, the condensate is delivered in an atomized, relatively thin, and heated state, to the salt. The salt, in turn, is heated, being delivered directly from the vacuum pans, in which it is dried, to the hopper 18 and revolving drum 19 of a mixer. This may be a common type of mixer, such as is used for mixing concrete, and comprising a revolving drum having internal baffles, by which the material charged therein is continually lifted and turned over and dropped, the result being to maintain a continuous shower of salt in the path of discharge of the spray gun. The discharge of the condensate by the spray gun is with sufficient force to bring about an impact of the condensate upon the salt crystals. Salt crystals are relatively hard and dense, and do not readily take up liquid smoke, particularly when the hydrous content has been removed therefrom. By the

method herein described, of discharging the condensate upon the crystals, under pressure, the salt is caused to take up a very great deal more of the liquid than they would take up if they were merely exposed to contact with the liquid. 70

I find a pressure of 25 pounds, at the gun, to operate satisfactorily, but this may be varied and still give satisfactory results.

Further, the application of the condensate to the salt is not restricted to a single passage of the salt in front of the spray gun, but, upon the contrary, the showering down of the salt and the discharge of the condensate thereon is continued until all of the salt crystals are heavily coated with the condensate. By this method I am able to produce a product of very great strength, as far as the smoke flavor is concerned, and this, of course, is what is primarily desired. 75 80 85

I find it of advantage to add 5% of brown sugar, preferably of the grade known in the trade as C or No. 7, and saltpeter and black and red pepper to the final product as marketed. This produces a complete smoke and sugar cure which renders it possible to give to meats the desired smoke flavor, while, at the same time, all of the labor incident to ordinary smoke house practice is avoided. 90

The present application is directed to the process herein described, including the impact of the condensate upon the salt, and to the resulting product, which includes the salt as a carrier. 95

In my co-pending application, No. 238,995, filed on the 9th day of December 1927, I am claiming the condensate as such, whether used with salt as a carrier or not, since it is apparent that this condensate freed of wood alcohol and dehydrated, is of utility as an article of commerce to be applied to the meats in its liquid form, as with a brush. 100 105

While I find the salt to be a convenient carrier I contemplate the application of the condensate to saltpeter, or any other granular or crystalline carrier which may be found suitable for the purpose. 110

Having described my invention, what I claim is:

1. The herein described method of manufacturing a meat cure which consists of impacting the concentrate resulting from the distillation of wood upon salt crystals. 115

2. The herein described method of manufacturing a meat cure product, which consists of atomizing the condensate resulting from the distillation of wood and forcibly discharging the same upon salt crystals. 120

3. The herein described method of manufacturing a meat cure product, which consists of atomizing the condensate resulting from the distillation of wood and forcibly discharging the same upon salt crystals, and in successive coatings. 125

4. The herein described method of manu- 130

facturing a meat cure product, which consists of atomizing the condensate resulting from the distillation of wood and forcibly discharging the same upon salt crystals, at elevated temperature.

5 5. The herein described method of manufacturing a meat cure product, which consists of atomizing the condensate resulting from the distillation of wood and forcibly discharging the same upon salt crystals, while 10 agitating the salt.

10 6. The herein described method of manufacturing a meat cure product, which consists of atomizing the condensate resulting from 15 the distillation of wood and forcibly discharging the same upon salt crystals, while agitating the salt in suspension.

7. The herein described method of coating 20 salt crystals with the concentrate resulting from the distillation of hard wood, which consists of maintaining the salt in a substantially continuous shower and discharging the concentrate in a heated condition and under the influence of heated air forcibly into contact with the salt crystals.

In testimony whereof I affix my signature.
ERNEST H. WRIGHT.
